Application January 9, 1951, Serial No. 13,714

Term of patent 14 years

(Cl. D58—6)

To all whom it may concern:

Be it known that we, Fred A. Vuillemenot and Fred R. High, residing at Raynham, in the county of Bristol and Commonwealth of Massachusetts, and at Attleboro, in the county of Bristol and Commonwealth of Massachusetts, respectively, have invented a new, original, and ornamental Design for a Bottle, of which the following is a specification, reference being had to the accompanying drawing, forming a part hereof, wherein:

Fig. 1 is an elevational view of a bottle, showing our new design;

Fig. 2 is a top view; and

Fig. 3 is a side elevational view thereof.

We claim:

The ornamental design for a bottle, as shown.

FRED A. VUILLEMENOT.

FRED R. HIGH.
